UNITED STATES PATENT OFFICE.

HARRY AGLOW, OF NEW YORK, N. Y., ASSIGNOR TO ARTCRAFT METAL STAMPING CORPORATION, A CORPORATION OF NEW YORK.

DESIGN FOR A BACKPLATE FOR LIGHTING FIXTURES.

Application filed January 29, 1925. Serial No. 12,186. Term of patent 7 years.

To all whom it may concern:

Be it known that I, HARRY AGLOW, a subject of the King of Great Britain, and a resident of the city of New York, county of Bronx, and State of New York, have invented a new original and ornamental Design for Backplates for Lighting Fixtures, of which the following is a specification, reference being had to the accompanying drawing, forming a part hereof.

In the drawing Figure 1 shows an elevation of the back plate for lighting fixtures, and Figure 2 is a diagrammatic outline in top elevation of the back plate for lighting fixtures.

I claim:

The ornamental design for a back plate for lighting fixtures substantially as shown.

HARRY AGLOW.
